T. W. SAUND

MIXING VALVE FOR GASES

Filed Aug. 4, 1924

Thomas W. Saunt Inventor

By James L. Morris
Attorney

UNITED STATES PATENT OFFICE.

THOMAS WILLFRED SAUNT, OF LEIGH-ON-SEA, ENGLAND.

MIXING VALVE FOR GASES.

Application filed August 4, 1924. Serial No. 730,019.

To all whom it may concern:

Be it known that I, THOMAS WILLFRED SAUNT, a subject of the King of Great Britain, residing at Leigh-on-Sea, Essex, 5 England, have invented new and useful Improvements in Mixing Valves for Gases, of which the following is a specification.

This invention relates to carburettors for providing the necessary explosive mixture 10 of fuel vapour and air, for supply to internal combustion engines.

My improved carburettor is of the type wherein there is a piston moving in a cylinder having its axis transverse to a thoroughfare at one end of which the air is admitted and at the other end the combustible mixture passes to the induction pipe of the engine, the fuel being admitted through a transverse inlet passage arranged on the 15 opposite side of the thoroughfare to the piston, the end of the piston opposite to the fuel inlet being made hollow or recessed. Such carburettors have heretofore been used only with liquid fuel, such as petrol, supplied as a mixture of liquid spray with air through a comparatively large bore of short 20 length closed at the bottom by a spraying device.

The object of my invention is to produce 25 a carburettor adapted for use with a gaseous fuel produced by the vaporization of petroleum or like heavy oil.

In the accompanying drawing,

Figure 1 is a vertical central section, and 30 Figures 2 and 3 are transverse sections on the line 2-2 and 3-3 respectively, of Figure 1, showing a carburettor constructed according to my invention.

A is the vaporizer-outlet, which is provided with a flange B to receive the flanged fuel inlet C of the carburettor that is secured in position by a nut D. The vaporizer 40 may be of the form described in the specification of my application for Letters Patent No. 557302, and is in the present drawing indicated in broken lines, 6 being the vaporizer, 7 a float chamber controlling the paraffin supply to the vaporizer, and 5 the burner which effects the evaporation.

The carburettor casing comprises an air-inlet branch E, which is enlarged inwards 50 at the bottom and extends to a sleeve F, that fits into a cylindrical branch G arranged coaxially with the fuel inlet C and is secured in position by a cover plate H. The sleeve F has a portion of its circumference cut away

at its lower end to form a port J which is arranged adjacent the air inlet branch 3 and also has a circular port K diametrically opposite said cut-away portion for the outlet of the mixture of fuel and air, the port K being arranged substantially above or at the level of the outlet of the fuel vapour inlet pipe I. The longer portion of the lower end of the sleeve F rests on a counter plate L having an upwardly extending cylindrical flange L' that fits into the sleeve and serves to centre the same. The counter-plate may be made selectively interchangeable with their counter-plates having flanges of different heights, if found desirable for the better control of the mixture by the throttle valve. The counterplate L rests on a flange I' on the fuel vapour inlet pipe I, and has a bore that fits loosely over such pipe. In the sleeve F there slides a piston M, the lower end of which is recessed at N to assist in forming an air cushion to receive the hot fuel vapour from the vaporizer outlet A. By this means, condensation of the vaporized fuel by coming into direct contact with metal surfaces at a lower temperature is prevented. As the lower end of the piston M approaches the lower end of the sleeve F it will, by throttling the port K, reduce the quantity of air and gas mixture passing to the outlet Y.

The piston is actuated by means of a rod O which has its head P in the form of a segment of a sphere. This rounded surface rests on a flat surface at the bottom of a recess in the upper surface of the piston and is held therein by means of a ring nut Q the bore of which is of such diameter as to leave a small amount of clearance 90 between its inner wall and the rod O. By this means any lack of alignment between the rod O and the bore of the sleeve F is automatically compensated for. The rod O is guided by means of an externally screw-threaded sleeve R, which fits into a correspondingly screw threaded socket S in the cover plate H and is secured in any desired position by means of a lock nut T, so as to limit the travel of the piston M in an upward direction.

A drain passage V is provided in the lowermost part of the air inlet E to carry off from the sump so formed any oil that may be drawn through the vaporizer into the carburettor in a liquid state.

W is a float chamber provided with a

water supply pipe W' for maintaining water available for being drawn into the air-inlet E of the carburettor through a passage X, in accordance with the suction of the engine. The passage X is provided at the upper end of its vertical limb with an air-inlet which is formed along the axis of a screw X' and serves to introduce air for spraying the water drawn into the carburettor and also for preventing the water from escaping from the chamber W by siphoning when the engine is not running. Such addition of water to the explosive mixture has been found to prevent preignition and to improve the combustion of the fuel in the engine cylinder. Y is the outlet for the mixture of fuel vapour and air, such outlet being connected to the induction pipe of the engine in a known manner.

By the construction shown, the sleeve F can be readily exchanged for another having ports J, K of different sizes and shapes, so as to enable the carburettor to be adjusted to engines of different powers, or to limit the speed of an engine if required. Moreover since the fuel vapour inlet pipe or nozzle I is held in position by the sleeve F, such pipe may be readily interchanged for a new one or for one of different size when required.

By arranging the port J at a low level in the air-inlet E, as shown, it is possible to ensure that the maximum quantity of air shall sweep across the inlet pipe or nozzle I for the gaseous fuel.

Moreover a blanking ring or perforated

diaphragm 3 can be supported at the entrance to the air-inlet E, to determine the maximum admission of air to the carburettor. This diaphragm is here shown as supported in a recess in the end face of the inlet branch E and secured in position by means of a ring 4 held against the inlet branch by studs and screws.

The improved carburettor enables a properly proportioned mixture to be obtained throughout the entire range of travel of the piston from closed to full throttle opening. The control is by the throttle alone which can be operated from the accelerator of the vehicle in any suitable known manner.

I claim:

A casing comprising a conduit adapted for connection at one end to an engine intake and open at the other end to the atmosphere, an inlet for vaporized fuel extending into said conduit transversely of the bore thereof, a cylindrical sleeve extending across said conduit co-axially of said fuel inlet, said sleeve being formed with an opening in that side adjacent the end of the conduit which is adapted to be connected to the engine intake, and with an arcuate port in the opposite side extending part way around said sleeve, the upper edge of said port terminating substantially at the upper edge of said fuel inlet, and a plunger-type throttle valve operable within said sleeve.

THOMAS WILLFRED SAUNT.

Witness:

HARVEY J. BAVERSTOCK.
